UNITED STATES PATENT OFFICE.

OSCAR E. SCHAEFER, OF ST. LOUIS, MISSOURI.

PROCESS OF MAKING BOOKS.

1,219,589.

Specification of Letters Patent. Patented Mar. 20, 1917.

Application filed June 12, 1916. Serial No. 102,115.

To all whom it may concern:

Be it known that I, OSCAR E. SCHAEFER, a citizen of the United States, and a resident of the city of St. Louis and State of Missouri, have invented a new and useful Improvement in Processes of Making Books, of which the following is a specification.

This invention relates to small cloth covered books, such as note books, pass books, pocket account books, and the like, and particularly to the cover and process of making it.

Note books, pass books, and the like having cloth covers and round corners as heretofore made have been of two kinds, one kind having the edges bound with cloth and the other kind having the edges sheared smooth. The cloth along sheared edges soon frays, and for this reason sheared edge note books look cheap. The objection to books with cloth bound edges is that they have to be covered by hand, which adds to the cost of the book.

The object of this invention is to produce a neat, serviceable book at a low cost, and the invention consists in the book and process of making it hereinafter described. Further objects of the invention appear in connection with the following description of the book and process of making it illustrated in the accompanying drawings. What the invention consists in is particularized in the appended claims.

The drawings illustrate the process of making a pass book with a window in the front cover. In the drawings, wherein the same reference characters represent the same parts for a book in the several views,

Figure 1 is a perspective view of the back of the leaves brought together for making a strip of three books, after sewing on the inside cloth reinforcement;

Fig. 2 is a similar view of the same after pasting on the card-board sides and the cloth outside cover;

Fig. 3 is a similar view of the same after turning in the edges of the cloth outside cover and punching the holes in the front cover for windows;

Fig. 4 is a plan view of the paper inner lining for the back and front covers, showing the window openings in the front lining with celluloid windows pasted over them;

Fig. 5 is a perspective view of the inside of the strip of books after the linings have

been pasted in and prior to severing the strip into separate books; and

Fig. 6 is a perspective view of a finished pass book.

In the book shown in the drawings, the top and bottom edges of the covers are sheared off, and the side edges of the covers are bound with cloth. This arrangement permits binding and covering three or more books at once in a single strip or blank, and then shearing the blank apart to produce the separate books. Referring to the drawings, the process consists of making up leaves 10 long enough for three books, bringing them together in book form, and sewing a binding strip of cloth 11 to the back of the leaves to make a single assemblage, as shown in Fig. 1. The card-board sides 12 are pasted to the strip 11, and the cloth outside cover 13 is pasted to the card-board sides, as shown in Fig. 2. Next, the edges 14 of the cloth cover are turned over the edges of the card-board sides and pasted along the inside of both to constitute the front and back covers, and three holes for window openings 15 are stamped through the cloth and card-board front cover, as shown in Fig. 3.

The front lining strip 16 and the back lining strip 17 are pasted to the inside of the front and back covers, respectively, overlapping the edges of the cloth cover 14 and reinforcing strip 11. The front lining strip has holes 18 in it located to correspond to the holes in the front cover for the window openings 15, and these holes are covered by pieces of celluloid 19 securely pasted at their edges to the strip 16. The celluloid windows are held between the strip 16 and the card-board front cover 12 across the window openings 15. The lining strips are long enough for three books, and are securely pasted to the card board covers 12, to the turned-in edges of the cloth cover 13, and to the edges of the reinforcing cloth strip 11, thereby covering the edges of the cloth, as shown in Fig. 5.

The blank thus formed is sheared or otherwise parted from edge to edge to divide it into three portions, each containing one window opening near its top; and the outer corners of each separate portion are sheared or rounded off to produce the completed book 19 shown in Fig. 6. The book thus produced has cloth bound side edges 14.

where the wear and tear is greatest, the ends 20 and round corners only being unbound, and has the aspect of a hand made book.

It is evident that changes in the shape and 5 arrangement of the various parts of the book and their manner of construction can be made without departing from the invention, and the invention is not restricted to the exact process described above nor to the 10 particular book shown in the drawings.

I claim the following as my invention:

1. The process of making cloth covered books which comprises combining the sides and leaves to form a strip of three or more 15 books, covering the sides with cloth, turning the side edges of the cloth covering in, and severing the strip transversely into three parts, whereby the top and bottom edges of each part are trimmed to constitute 20 a finished book.

2. The process of making cloth covered books with round corners which comprises assembling the sides and leaves to form a strip of three books, pasting a covering of 25 cloth upon the outer side of the strip, turning the side edges of the cloth covering in, and severing the strip transversely into three parts, the corners of each part being cut round, to constitute a finished book.

3. The process of making cloth covered books with round corners and window 30 openings which comprises securing together

the cloth covering, sides and leaves to form a strip of three books having front and back covers, turning the side edges of the 35 cloth covering in, cutting window openings in the front cover, lining the covers with strips having transparent windows covering said openings, severing the strip into three parts and trimming the corners of each part 40 round to constitute a finished book.

4. The process of making cloth covered books which comprises assembling the leaves and front and back sides with a binding 45 strip, covering the sides and strip with cloth, turning the side edges of the cloth covering in, and cutting the top and bottom edges square and the corners round to constitute a finished book.

5. The process of making cloth covered 50 books which comprises assembling the leaves and front and back sides with a binding strip, covering the sides with cloth, turning the side edges of the cloth covering in, cutting a window opening in the front side 55 and covering, applying a lining strip to said front side having a window conforming to said window opening, and trimming the top and bottom edges to constitute a 60 finished book.

Signed at St. Louis, Missouri, this eighth day of June, 1916.

OSCAR E. SCHAEFER.
